UNITED STATES PATENT OFFICE.

ARTHUR B. WARING, OF NEW YORK, N. Y.

PROJECTILE.

1,192,586.

Specification of Letters Patent. Patented July 25, 1916.

Application filed May 17, 1915. Serial No. 28,526.

To all whom it may concern:

Be it known that I, ARTHUR B. WARING, a citizen of the United States of America, and a resident of New York, county and 5 State of New York, have invented certain new and useful Improvements in Projectiles, of which the following is a specification, reference being had to the accompanying drawings, forming a part thereof.

10 My invention relates to projectiles and it has for one of its objects to provide a projectile or an attachment therefor that shall be particularly adapted for the purpose of cutting and destroying fortification entanglements, of barbed wire or the like.

15 Other objects and advantages of my invention will be set forth hereinafter, and in order that my invention may be thoroughly understood I will now proceed to describe 20 the same in the following specification and then point out the novel features thereof in appended claim.

Referring to the drawings: Figure 1 is a sectional elevation of the outer end of a gun 25 or cannon showing a projectile arranged and constructed in accordance with my invention, in position to be discharged therefrom. Fig. 2 is a front view of the same projectile. A modified structure which also embodies 30 my invention and in which the projectile is made in two independent parts, one constituting a carrier for the other, is shown in Fig. 3. Fig. 4 corresponds to Figs. 1 and 3 and illustrates still another modification of 35 my invention.

In Fig. 1, 10 represents a gun and 11 the body of the projectile. The projectile may be of any suitable form and as shown has the general form of a cylinder with a blunt 40 pointed end 12. The projectile body 11 has a central opening 14 in its front end which forms a socket to receive a rod or bar 15 which extends beyond the muzzle of the gun. Secured to the outer end of the bar is a 45 frame composed of a plurality of inclined arms 16 which converge to a point like a spear and the outer surfaces of which are saw toothed as shown at 17. In addition to the inclined arms the frame comprises a supporting ring 18 which interconnects the 50 outer ends of the arms and a conical block 19 on which the inner ends of the arms are mounted. The block 19 is affixed to the outer end of the rod 15. The structure 55 constitutes a mighty spear of larger diameter

than the bore of the gun which may be hurled at the enemy and is particularly designed to cut away barbed wire entanglements which are very troublesome and dangerous, being frequently charged with high 60 voltage electric energy.

In the modification of Fig. 3 the projectile proper acts as a carrier and picks up the cutting spear as it leaves the muzzle of the gun. In this arrangement the spear head 65 comprises a central socket 20 which has a ring-shaped body 21 with a tapered bore and heavy resilient projections 22 partially closing the front end of the ring, and outwardly extending arms 23 which correspond 70 to the arms 16 and are rigidly attached to the ring 21. The spear head is adapted to be picked up by the projectile as it leaves the muzzle of the gun and carried to the target. The ring is shaped to wedge itself 75 into the projectile body and the resilient projections are for the purpose of preventing injury to the spear head as it is picked up by the projectile.

Referring to Fig. 4, the spear attachment 80 is similar to that of Fig. 1 and corresponding parts are designated by the same reference characters. The inner end of the rod 15 however, instead of being set into a socket 14 in the projectile, is tapered and is adapted 85 to be engaged by the projectile which has a tapered opening 24. The intention is that the pointed end of the rod shall be loosely started into the taper opening in the projectile at the time the gun is discharged. 90 The projectile as it advances will then force the engaging parts firmly together and carry the spear attachment out with it. Instead of having the rod 15 secured to the projectile, it may be found desirable to have its 95 inner end revolvably seated in a socket in the projectile in order to permit the projectile body to follow the rifling of the gun and rotate at high speed without necessarily causing the spear attachment which is relatively large, to rotate at the same speed, the rotation imparted to the spear head being due merely to the friction of the bearing between the two loosely connected parts. 100

It is evident that the structure of my invention may be varied without departing from the spirit and scope of my invention and I intend that only such limitations be imposed as are indicated in the appended 105 claim.

What I claim is:

The combination of a projectile body adapted to be discharged from a rifle, and a separate projectile rider arranged to be disposed beyond the muzzle of the rifle before the rifle is discharged, said rider comprising a ring-shaped body and contracting resilient projections extending forwardly and inwardly therefrom, adapted to be wedged onto the projectile body and propelled with

it, and a plurality of symmetrically disposed inclined arms extending outwardly and backwardly from the ring and rigidly affixed thereto, said arms having saw toothed edges, and means for rigidly interconnecting 15 said arms at points back of said ring.

In testimony whereof, I have hereunto set my hand this 14 day of May, 1915.

ARTHUR B. WARING.
